UNITED STATES PATENT OFFICE.

LEONARD L. CONKEY, OF GRAND RAPIDS, MICHIGAN, ASSIGNOR TO THOMAS OLINGER,
OF HOLLAND, MICHIGAN.

CHAIN-BUCKLE.

1,134,994.

Specification of Letters Patent.

Patented Apr. 13, 1915.

Application filed March 8, 1913. Serial No. 752,882.

To all whom it may concern:

Be it known that I, LEONARD L. CONKEY, a citizen of the United States of America, residing at Grand Rapids, in the county of Kent and State of Michigan, have invented certain new and useful Improvements in Chain-Buckles; and I do hereby declare the following to be a full, clear, and exact description of the invention, such as will enable others skilled in the art to which it appertains to make and use the same.

My present invention relates to chain buckles, and its object is to provide a device which shall be simple and economical in construction, which shall without the use of a spring engage and securely hold the chain to which it is applied, and which may be readily fastened and unfastened without unduly tightening the chain; other objects appearing hereinafter. These objects are attained by, and my present invention finds a preferable embodiment in, the structure hereinafter described and illustrated by the accompanying drawings, in which:—

25 Figure 1 is a perspective view of a chain buckle applied to a chain, and illustrating the closed or operative position of the device; and Fig. 2 is a like view of the buckle in open or inoperative position.

30 To the hasp or rim 1, preferably U-shaped as shown, is pivoted or fulcrumed at 6 to the lever 2, the arm 7 which forms the tongue and to the other arm 8, of which forms the chape is fastened as at 3 the end 35 link of the chain 4 in connection with which the buckle is used. The buckle tongue 7 is held by the hasp 1, in the usual abutting engagement of such parts, against movement in one direction, being oppositely movable.

40 This tongue is provided with a slot 5 of sufficient width and depth to admit one of the chain links edgewise, the sides of the slot engaging the next link, which is necessarily in transverse relation to such admitted link.

45 It will be seen that as the tongue is moved in the direction of the arrow in Fig. 1 to unfasten the buckle, the chain is loosened at the chape when necessarily tightened at the tongue end, and that therefore the buckle 50 may be the more readily unfastened when the chain is tight about any object; and also that the degree of this loosening at the chape

relatively to the necessary tightening at the tongue depends on the proportional length 55 of the lever arms 7 and 8 and to their angular relation on the fulcrum point; and also that by reason of the stress exercised on the lever by the tightening chain, the lever is held in engagement with the hasp 1. 60

This invention is a particular improvement on the device shown in my former Patent No. 395,742, issued January 8th, 1889. It will be seen that it is much more durable in construction and that by eliminating the spring, for actuating the tongue, I have overcome the objection that the spring was necessarily fragile and liable to break, thus making the device inoperative. When the device is applied to chain 4 it 70 exerts tension upon the member 7 through the bolt or fastening 3 which obviously forces the slotted terminal of the lever 7 upwardly into engagement with the transversely disposed link of said chain thereby 75 rigidly holding the clasp in position.

Not confining myself to details of construction shown or described, I claim:

In a chain buckle, a hasp member of U-shaped formation, the free ends of said hasp 80 member being enlarged, a lever pivoted between the enlarged ends of said hasp member, said lever being reduced at its outer end and extending beyond the enlarged ends of the hasp member, said lever having a notch 85 in its inner end, and a chain connected to the reduced end of the lever beyond the enlarged ends of the hasp member and adapted to engage the notch in said lever, the inner end of the lever being greater in width than 90 the distance between the sides of the hasp member, and longer than the inner longitudinal dimensions of said hasp member, said lever being curved to conform to the curvature of the upper side of the hasp 95 member whereby the inner end of the lever will engage the entire upper side of the hasp member and relieve the pivoted portion thereof from all strain substantially as and for the purposes set forth. 100

In testimony whereof I affix my signature in presence of two witnesses.

LEONARD L. CONKEY.
